UNITED STATES PATENT OFFICE.

THEODORE F. BOURNE, OF MONTCLAIR, NEW JERSEY.

CARBURETER.

1,153,435.

Specification of Letters Patent.

Patented Nov. 2, 1915.

Application filed July 31, 1914. Serial No. 854,238.

To all whom it may concern:

Be it known that I, THEODORE F. BOURNE, a citizen of the United States, and resident of Montclair, Essex county, New Jersey, have invented certain new and useful Improvements in Carbureters, of which the following is a specification.

My invention has reference to improvements in carbureters particularly adapted for use on internal combustion engines, and one of the objects of my invention is to provide simple and efficient means for providing an initial or primary mixture of liquid fuel and air, and for combining such mixture with air to provide a relatively correct mixture for the varying requirements of the engine.

My invention comprises novel details of improvement and combinations of parts that will be more fully hereinafter set forth and then pointed out in the claims.

Reference is to be had to the accompanying drawings wherein,

Figure 1 is a vertical section of a carbureter embodying my invention; Fig. 2 is a substantially horizontal section taken through the several air passages; Fig. 3 is a section on the line 3, 3, in Fig. 2; Fig. 4 is a detail view of the air valve shell, and Fig. 5 is a detail illustrating means for controlling the needle valve for starting, etc.

In the accompanying drawings the carbureter casing has a carbureting or mixing chamber 1, shown provided with a suitable throttle valve 2, and having a main air inlet opening or passage 3. At 4 is a passage for liquid fuel that leads into the carbureting chamber from a source of fuel supply, such as a constant-level fuel bowl or chamber 5, shown having a float 6 and inlet controlling valves 7, to maintain the fuel level (a) as required, which may be arranged in any suitable manner. At 8 are air supply passages leading into the carbureting chamber, and communicating by means of jets or nozzles 9 within the carbureting chamber with the fuel supply passage 4. The air passages 8 are shown opening through the wall of carbureting chamber 1, and inclined upwardly and inwardly therein at a suitable angle, and said passages 8 are shown arranged circularly and spaced apart to permit air from the inlet 3 to flow in divided streams past said passages to mingle with the mixture produced in the passages 8. It will be noted that the single passage 4 supplies fuel to a

plurality of jets 9, which jets branch outwardly and upwardly from passage 4 to the air passages 8. While the jets 9 may be of definite or set dimensions yet in order to enable the control of the flow of fuel from passage 4 to the jets 9, I have shown a needle valve 10 to control passage 4 below the communication therewith of the jets 9. The needle valve 10 is shown passing through a suitable bore 10^b in the carbureting chamber that is connected with passage 4. The casing is illustrated as provided with a lower portion 1^b with which the passage 4, branch jets 9, and air passages 8 are cast integrally, and with an upper portion 1^c suitably secured to the lower portion 1^b, the meeting joint of the parts 1^b, 1^c being so disposed as to enable ready drilling of the passages 8 and jets 9. A band *a* surrounding the carbureting chamber may be adjusted up or down, and may be held in set position by screw *b*, whereby the admission of air into the passages 8 may be controlled.

With the construction set forth the needle valve may be set to permit the required amount of fuel to flow to the several jets 9, and during operation of the engine the suction therefrom will cause air to flow through the passages 8 and carry liquid fuel therewith from the respective jets 9, thereby producing independent streams of relatively rich mixture in each passage, which mixtures flowing through the upper orifices of said passages 8 into the carbureting chamber will be mixed or diluted therein with air entering the carbureting chamber from below, or through inlet 3, such air being divided into various streams or portions as it passes between several passages 8 and the branch jets 9 whereby the liquid fuel is finely vaporized and an ultimate mixture of fine quality is produced. As the single needle 10 controls the supply of liquid fuel to the several jets 9, a simple means is provided for controlling the flow from the several jets without requiring each jet to be separately controlled, thus producing uniformity in the jet supply to the carbureting chamber.

While the air entering the carbureter, through the inlet 3, may be controlled in any suitable manner, I have shown means for adjusting and regulating, at will, the amount of primary or main air admitted, together with a valve for automatically controlling the inflow of further or auxiliary air. To this end I provide a shelf or cage

11 adapted to fit adjustably in a seat or bore 12 in the main casing, which shell or cage has a closure 11^a at one end, and is shown open at the opposite end, and open at the 5 side portion 11^b for communication with the air inlet 3. Shell or cage 11 also has a side opening 11^c adapted to register with an air opening in the wall of the casing, shown at 14, and the lower edge portion of the wall 10 portion 11^d of such shell or cage below the opening 11^c is shown adapted to register with an air opening in the casing, shown at 15, the lower edge of shell 11 being adapted to be adjusted toward and from a wall 1^d 15 of the casing. Between opening 11^c and the lower open portion of shell or cage 11 the latter has a valve seat 16, and at 17 is a valve adapted to said seat and shown mounted to slide upon an adjustable stem or rod 20 18 having threads 18^a engaging threads 19 that are upon the closure 11^a, whereby said stem may be adjusted. Valve 17 may be made of leather or other suitable material. A spring 20 upon said stem, between said 25 valve and a stop 21 on said stem, maintains the valve normally closed. From this it will be understood that the shell or cage carrying the valve may be adjusted relatively to opening 15 and wall 1^d to admit the desired 30 amount of main or primary air into the carbureting chamber according to the requirements of the engine, and that valve 17 will open more or less to admit further or auxiliary air as required. It will be understood that when shell or cage 11 is adjusted the setting of the spring tension against valve 17 is independent of such adjustment. The opening 14 with respect to the opening 35 11^c of shell 11 is such as to always supply the full amount of air for the opening 11^c when shell 11 is adjusted up or down with respect to opening 15. The part 1^e of the casing wall may be omitted, thus combining the openings 14 and 15 in one opening. The 40 arrangement described enables connection to be made through an inlet fitting 22 on the main casing for the supply of heated air through the inlet opening 3 when desired. Shell or cage 11 may be held in set position 45 50 by a screw 11^f carried by the casing.

While the needle valve 10 may be arranged in an ordinary manner, I have, in the accompanying drawings, shown said valve 10 provided with threads 10^a meshing 55 with threads in a member or plug 24, that is slidable in a bore 25^a provided in an extension or stem 25 projecting from the casing and in which the bore 10^b is partially located. The member or plug 24 may be 60 kept from rotation in extension 25 by means of a pin 26 projecting from said plug and slidable in a slot 27 in extension 25, and at 65 28 is an arm or lever shown pivotally carried by the carbureter, at 29, and provided with a suitable slot 30 receiving pin 26, said

lever being retained in set position by a spring, shown at 31, suitably connecting said lever with the casing. With this arrangement the needle valve may be rotated in plug 24 to control the flow from the jets 70 9, and when it is desired to increase the richness of the mixture, as for starting or for heavy work, the lever 28 may be rocked, whereby the slot 30, acting upon pin 26, will cause plug 24 to move outwardly and 75 correspondingly carry the valve 10 with it, thereby raising said valve more or less from its seat. The needle valve returns to its original set position without changing the position of the valve with relation to its 80 plug 24, since normally said plug may rest upon the bottom of the bore 25^a. The needle valve and the means to vary its position without changing its setting in its supporting member or plug 24 are independent of 85 the throttle. A lock nut 32 upon valve 10 may be provided to retain the same set upon member or plug 24.

While I have illustrated the air passages 8 and fuel jets 9 as cast integrally with the 90 casing, it will be understood that said passages and jets may be cast or formed separately and secured to the casing, preferably to the walls thereof, by solder, in which case passage 4 may also be cast integrally 95 with the jets 9 and suitably connected with the constant-level fuel supply chamber.

Changes may be made in the details of construction and arrangement of parts set forth, as the same may be varied, within 100 the scope of the appended claims, without departing from the spirit of the invention.

Having now described my invention what I claim is:—

1. A carbureter comprising a carbureting chamber, a plurality of air passages therein and spaced apart for the passage of air between the same within said chamber, and a fuel supply passage having a plurality of jets communicating with said air passages 105 respectively.

2. A carbureter comprising a carbureting chamber, a plurality of air passages spaced apart within said chamber and extending inwardly and upwardly thereinto and opening at their intake ends to atmosphere through the wall of said chamber and permitting the flow of air between certain of said passages, a plurality of jets within said chamber and communicating respectively 115 with said air passages, and means to supply liquid fuel to said jets.

3. A carbureter comprising a carbureting chamber, a plurality of air passages spaced apart within said chamber and extending 120 inwardly thereinto and communicating at their intake ends with atmosphere and permitting the flow of air through said chamber between certain of said passages, a plurality of jets extending outwardly within 125 130

- said chamber and communicating respectively with said air passages between their inlet and outlet orifices, and a passage for liquid fuel communicating with said jets.
- 5 4. A carbureter comprising a carbureting chamber, a plurality of air passages inclining upwardly and substantially transversely therein and open to atmosphere at their outer ends, a plurality of jets within said 10 chamber inclined upwardly and outwardly and communicating respectively with said air passages, the air passages and jets being respectively spaced apart permitting the flow of air between the same, and a liquid 15 fuel passage entering said chamber and communicating with said jets at their inner portions.
5. A carbureter comprising a carbureting chamber, a plurality of air passages circularly disposed within said chamber and spaced apart for the passage of air between and past the ends of said passages, a plurality of jets circularly disposed within said chamber and spaced apart below said air 25 passages, said jets communicating at their outer ends with said air passages respectively, a constant level fuel supply source, and a passage connecting the latter with said jets, said last named passage extending 30 within said chamber below said jets and passages permitting the flow of air past the same.
6. A carbureter comprising a casing having a portion provided with a plurality of 35 air passages therein, a plurality of jets communicating with said passages, said jets and passages being spaced apart to permit air to pass between the same, said casing having a portion above said passages secured there- 40 to, and a throttle valve carried by the casing above said passages and jets.
7. A carbureter having a carbureting chamber and provided with a plurality of air passages spaced apart within said chamber to permit the flow of air between certain 45 of said passages within said chamber, the inner discharge orifices of said passages terminating within said chamber in spaced relation for the flow of air past the same, a plurality of fuel jets leading to said passages respectively between their inlets and outlets, and means to supply fuel to said jets.
8. A carbureter comprising a carbureting 50 chamber having an air inlet and a mixture outlet, a plurality of air passages spaced apart within said chamber between said inlet and outlet permitting the flow of air between said passages within said chamber,
- 55 said passages having air inlets, and having mixture orifices within said chamber, and means to supply liquid to said air passages.
9. A carbureter comprising a carbureting
- chamber having an air inlet and a mixture outlet, a plurality of air passages spaced apart within said chamber between said inlet and outlet providing spaces between said 60 passages permitting the flow of air from said inlet between said passages within said chamber, said passages having inlets communicating with atmosphere through the wall of the chamber and having mixture orifices within said chamber, a plurality of liquid fuel jets communicating respectively with said passages, and a fuel passage communicating with said jets.
10. A carbureter having a chamber, a plurality of air passages spaced apart within said chamber and having exit orifices spaced apart within and at a distance from the wall 65 of said chamber, permitting the flow of air between said passages and orifices, liquid fuel jets spaced apart within said chamber permitting the flow of air between said jets and respectively communicating with said 70 air passages, and a fuel supply passage within said chamber disposed between and communicating with said fuel jets.
11. A carbureter comprising a chamber having an air inlet and a mixture outlet, a plurality of air passages spaced apart within said chamber providing spaces therebetween permitting the flow of air between said 75 passages, said passages communicating with atmosphere through a wall of said chamber and having exit orifices spaced apart within said chamber between said inlet and outlet, liquid fuel jets communicating with said air passages, a fuel supply passage communicating with said fuel jets, 80 and means to regulate the flow of air through said air inlet to control the flow of air within said chamber past said exit orifices of said air passages and between the latter.
12. A carbureter having a chamber, a plurality of air passages spaced apart within said chamber and opening at their intake ends through a wall of said chamber, said 85 passages having their outlet orifices spaced apart within said chamber at a distance from the wall of the chamber, a plurality of jets communicating with said passages respectively, means to supply liquid fuel to said jets, and a band surrounding said chamber arranged to be adjusted relatively to said 90 inlet ends of said air passages to control the flow of air into said passages.
